UNITED STATES PATENT OFFICE.

JOHN H. PLACE, OF DECATUR, ILL., ASSIGNOR OF TWO-THIRDS TO DAVID R. ALEXANDER AND THOMAS P. MATTHEWS, BOTH OF SAME PLACE.

CIRCULAR-KNITTING MACHINE.

SPECIFICATION forming part of Letters Patent No. 358,983, dated March 8, 1887.

Application filed September 16, 1886. Serial No. 213,660. (No mode.)

To all whom it may concern:

Be it known that I, JOHN H. PLACE, of the city of Decatur, county of Macon, and State of Illinois, have invented certain new and useful 5 Improvements in Circular - Knitting Machines, of which the following is a specification.

My invention relates to circular-knitting machines for knitting "double-knee" stockings; and it consists in certain details of construction and combinations of parts, as hereinafter set forth and claimed.

In the drawings accompanying and forming a part of this specification, Figure 1 is a side view of my machine. Fig. 2 is a plan of the cam-cylinder. Fig. 3 represents opposite sides of the cam-cylinder in central vertical section on dotted line X in Fig. 2, the cams occupying one of two possible operative positions. Fig. 20 4 represents opposite sides of the cam-cylinder in central vertical section on dotted line x in Fig. 2, the cams occupying the other of two possible operative positions. Fig. 5 is a vertical section of a portion of the cam-cylinder 25 on dotted line Y in Fig. 2. Fig. 6 represents a portion of the fabric which my machine is designed to knit, the interstices being unduly enlarged the better to show the peculiarities of the texture and one thread being darkened 30 for the same purpose. Figs. 7 and 8 represent series of needles on right planes which are intended to illustrate, in a manner to be herein-after specified, certain steps in the operation of the machine and the formation of the fabric.

35 The needle - cylinder s is distinguishable from needle-cylinders as commonly constructed by its unusual length only. The needles used are of two sets, one set long and the other set short.

40 e', Fig. 3, indicates a short needle in its proper vertical position with relation to the contiguous cam-cylinder.

d', Fig. 4, indicates a long needle in its proper vertical position with relation to the 45 contiguous cam-cylinder. The needles of one set, d', are arranged consecutively on one side of the needle-cylinder and alternately with the needles e' of the other set on the opposite side of the needle-cylinder.

50 The cam-cylinder is composed of two por-

tions, m and e, one above the other, the internal operative surfaces of one being vertically coincident with the other, and the upper portion extending down around the lower portion. Each portion of the cam-cylinder is provided 55 with a set of cams, m', in the upper and e' in the lower portion, and said cams correspond one set with the other in size and shape. Lower portion, e, of the cam-cylinder is provided at its lower termination with an annular flange, e'', that projects outwardly on a horizontal plane. That part of the upper portion of the cam-cylinder which embraces the lower portion is also provided at its lower termination with an annular flange, m''', that 60 rests in contact with flange e'', but does not extend so far.

Secured to the upper outer surface of flange e'' is an annular band, f, provided with an inner and under circumferential recess, that fits 70 over flange m'''. Concentric slots h penetrate the band vertically, and set-screws i secure said band to flange e'' in a manner permitting rotatable adjustment.

At points directly opposite are apertures g 75 in the upper surface of band f, and a bolt, n, having vertical motion in a casing, k, on the downward and outward extension of the cam-cylinder engages one of said apertures and makes the relative positions of the different 80 parts of the cam-cylinder temporarily rigid. A spring, k', in casing k causes the bolt to surely engage the apertures, and a projection, l, furnishes means for readily raising the bolt. Brackets q are attached to the upper portion 85 of the cam-cylinder at points directly opposite, and carry, in addition to the customary thread-guides o' and p', the auxiliary guides o and p. The comb r (shown in Fig. 1) differs from ordinary combs only in having an opening through 90 which a thread may be passed. The dovetail block m'' in Figs. 3 and 4 forms a portion of the needle-supporting band opposite the cams in the upper portion of the cylinder, and its removal permits the ready insertion of the 95 long needles.

The long needles are operated by cams e', the short needles are operated by cams m', and said needles are all operated consecutively without regard to sets; or the needles of one 100

set are operated alternately with the needles of the other set, according as the cams are arranged vertically coincident, as shown in Fig. 4, or opposite, as shown in Fig. 3.

5 It is essential that the vertical coincidence of the cams should be very precise, in order that the operation of the needles may be regularly continuous, and the slots *g* and screws *i* furnish means whereby the vertical positions 10 of the cams may be made to exactly coincide. To knit a stocking with my machine, the two portions of the cam-cylinder are placed with their cams vertically coincident, (see Fig. 4,) and the needles are set up with thread *b* in any 15 well-known manner. Then, as the knitting proceeds, all the needles are operated in regular succession, and an ordinary one-thread fabric is produced, as shown in the lower portion of Fig. 6. When the knee of the stocking is approached, bolt *n* is raised out of an aperture, 20 *g*, and the upper portion of the cam-cylinder is given a semi-revolution on the lower portion, carrying the cams into the opposing positions shown in Fig. 3 and the bolt into the opposite aperture. Thread *a* is now introduced, 25 preferably through the comb, as indicated in Fig. 1, and when the knitting is recommenced one thread is knitted on one set of needles by one set of cams and the other thread is knitted 30 on the other set of needles by the other set of cams, that part of the fabric formed on the needles of both sets alternately arranged appearing as indicated in the upper left portion of Fig. 6, and that portion of the fabric formed 35 on needles of one set consecutively arranged appearing as indicated in the upper right part of Fig. 6. When the knee portion of the stocking has been knitted in this manner, bolt *n* is again raised and the cams again carried into 40 a vertically-coincident position by giving the upper portion of the cam-cylinder a semi-revolution on the lower portion. Thread *a* is dispensed with, and the stocking is completed with one thread in any well-known manner.

45 In Fig. 6 *a* represents the thread that is knitted on needles *c* only. *b* represents the thread that is knitted on all the needles when the cams are vertically coincident, and on needles *d* only when the cams are oppositely arranged.

50 The wales *c* are knitted on needles *c*. The wales *d* are knitted on needles *d*, the connecting-threads of each set of wales being interknitted with the intervening wales, as shown.

In Fig. 7 the relative positions of the threads 55 are shown as they appear in the machine immediately after thread *a* has been knitted. In Fig. 8 the relative positions of the threads are shown as they appear in the machine immediately after thread *b* has been knitted.

60 The needles stand above the cylinder when not in operation, and the thread that is knitted by one set of needles is laid against the needles of the other set to be interknitted with the wales subsequently formed thereby. The

65 floating portion *a* of thread *a*, which is formed by being carried around the consecutively-arranged needles *d* and passed to the inside of

the cylinder by their subsequent operation, is cut away after the stocking is knitted.

I do not claim herein either the fabric or the stocking described, the former being embodied in my application No. 158,974, filed March 16, 1885, and the latter in my application No. 199,005, filed April 15, 1886.

Having thus described my invention, I claim as new and desire to secure by Letters Patent—

1. The combination of a needle-cylinder having two sets of needles of different lengths, with a cam-cylinder composed of an upper portion and a lower portion, each having a set of cams and having an independent adjusting rotation and a common operative rotation, as and for the purpose set forth.

2. The combination of a needle-cylinder having two sets of needles of different lengths, the needles of one set being continuously arranged on one side of the cylinder and arranged alternately with the needles of the other set on the opposite side of the cylinder, with a cam-cylinder composed of an upper portion and a lower portion, each having a set of cams and having an independent adjusting rotation and a common operative rotation, as and for the purpose set forth.

3. The combination of a needle cylinder having two sets of needles of different lengths with a cam-cylinder composed of an upper portion and a lower portion having their inner surfaces vertically coincident, the lower portion having an outwardly-projecting annular flange at its lower termination, and the upper portion extending down around the lower portion to the flange thereof, where it terminates in an annular flange outwardly projecting, an annular band on the flange of the lower portion of the cam-cylinder, embracing the flange on the upper portion, a set of cams in each portion of the cam-cylinder, and means whereby the said cams may be adjusted and held either vertically coincident or approximately opposite, as and for the purpose set forth.

4. The combination of a needle-cylinder having two sets of needles of different lengths with a cam-cylinder composed of an upper portion and a lower portion having their inner surfaces vertically coincident, the lower portion having an outwardly-projecting annular flange at its lower termination, and the upper portion extending down around the lower portion to the flange thereof, where it terminates in an annular flange outwardly projecting, an annular band on the lower flange, embracing the upper flange and having apertures or recesses at opposite positions, a set of cams in each portion of the cam-cylinder, and a bolt having vertical motion on the upper portion of the cam-cylinder in position to engage the recesses of the band, as and for the purpose set forth.

JOHN H. PLACE.
